Attorney

UNITED STATES PATENT OFFICE.

JAKE N. CRASILNECK, OF SAN ANTONIO, TEXAS.

BINDING FOR SHOE-HEEL FACINGS.

Application filed September 4, 1924. Serial No. 735,917.

To all whom it may concern:

Be it known that I, JAKE N. CRASILNECK, a citizen of the United States of America, and resident of San Antonio, in the county 5 of Bexar and State of Texas, have invented certain new and useful Improvements in Bindings for Shoe-Heel Facings, of which the following is a specification.

This invention relates to trimmings for 10 shoe heels, and has for an object the provision of novel means whereby the ornamental facings of shoe heels such as satin, leather material or the like, used for finishing the exterior of shoe heels, may be protected at 15 the lower edge and prevented from being displaced through wear or exposure to dampness.

It is an object of this invention furthermore to produce a finish between the heel 20 cap and the heel facings while at the same time producing a finished and artistic effect to the said heel of a shoe.

It is a further object of this invention to 25 produce a protector of the character indicated having novel means whereby it may be secured in place against accidental displacement under ordinary conditions of use and by means which are comparatively inexpensive.

With the foregoing and other objects in 30 view, the invention consists in the details of construction, and in the arrangement and combination of parts to be hereinafter more fully set forth and claimed.

In describing the invention in detail, reference will be had to the accompanying 35 drawings forming part of this application wherein like characters denote corresponding parts in the several views, and in 40 which—

Figure 1 illustrates a view in elevation of a shoe heel with a device embodying the invention applied thereto;

Figure 2 illustrates a view in elevation of 45 the front of the heel; and

Figure 3 represents a plan view of the heel with the cap removed.

In these drawings, 5 denotes a conventional type of heel for ladies' shoes, and 50 usually such heels have a facing 6 of fabric or leather. It is the purpose of this inventor to provide a finish in the nature of a binding at the joint between the facing of the heel and the cap 7 of the heel. With

the foregoing object in view, a binding 8, 55 which is in the nature of a metallic plate or band, is shaped to conform to the external configuration of the heel and it is of such size as to embrace the edge of the facing to prevent the facing from being 60 frayed at its edges and it is furthermore an object to have the band of such configuration as to form a seat for the inner edge of the cap in order that an artistic appearance may be given the heel of the shoe at 65 the junction of the facing and cap.

The band has a transversely disposed bar 9 extending across it at the lower edge and this bar is intended to overlie a portion of the end of the heel and to be covered 70 by the cap when the said cap is secured in place. The cap may be secured by conventional fastenings such as are employed for this purpose, but the inventor does not wish to be limited with respect to these features, 75 as any of the well known expedients for securing the cap on French heels may be used in connection with the invention.

The band 8 has an upwardly extending 80 apron 10 which serves to protect the facing of the heel and this apron may be of different areas, according to the size of the heel or the ornamental effect desired by the manufacturer.

I claim:

1. The herein described heel binding comprising a band to embrace a heel and the facing thereof at its lower edge, a bar extending across the band at its lower edge to engage the heel of a shoe, and a cap secured to the heel at the lower edge of the band. 85

2. In a binding for shoes, a band to embrace the heel of a shoe and its facing at 90 its lower edge, and a cap of slightly greater diameter than the band secured to the heel to retain the band on the heel. 95

3. The herein described heel binding comprising a band adapted to a heel and the facing thereof at its lower edge, a bar extending across the band at its lower edge to engage the heel of a shoe, the said bar limiting the upward movement of the band, an apron forming an extension of the band 100 at the front and engaging the front surface of a heel, and a cap on said heel at the lower edge of the band. 105

JAKE N. CRASILNECK.
